UNITED STATES PATENT OFFICE.

HENRY H. DOERING AND CHARLES DOERING, OF CHICAGO, ILLINOIS.

BUTTER-PRINT MACHINE.

1,384,245.

Specification of Letters Patent. Patented July 12, 1921.

Application filed September 2, 1920. Serial No. 407,644.

To all whom it may concern:

Be it known that we, HENRY H. DOERING and CHARLES DOERING, citizens of the United States, and residents of Chicago, in 5 the county of Cook and State of Illinois, have invented certain new and useful Improvements in Butter-Print Machines, of which the following is a description, reference being had to the accompanying drawings, 10 which form a part of our specification.

Our invention relates to a power operated butter print or molding machine which will be self-feeding; wherein the butter or butter substitute will not be subjected to a too 15 great pressure at the initial charging end; with the receiving end of the chamber or receptacle portion of the machine being such that pressure on the material will be retarded and operation of the machine made 20 automatic; while the size of the prints may be controlled and varied through simple, adjustable mechanism.

One object of our invention is to provide 25 means whereby the material will not only be fed or conveyed from the receiving to the discharging end of the machine, but which means is of such formation and so related to the interior of the receptacle, that a faster and more uniform action is obtained; said means in conjunction with improved moisture distributing means, which 30 enables a larger percentage of moisture to be provided in the product or butter, producing an improved product having a 35 smoother grain and more uniform blend than has heretofore been provided.

The invention provides a machine of the character described, wherein the blending, moisture providing and print forming operations are accomplished by a single unit, which eliminates the use of a separate blending machine and therefore results in a great saving of time and labor, while also providing a more sanitary product.

40 45 The purposes and advantages of our improved machine will be more readily comprehended from the following detailed description of the drawings, wherein:

Figure 1 is a side elevation of our improved machine.

Fig. 2 is a top plan view thereof.

Fig. 3 is a longitudinal sectional view taken on the line 3-3 of Fig. 2, looking in the direction of the arrows.

Fig. 4 is a vertical sectional view taken 55 on the line 4-4 of Fig. 1, looking in the direction of the arrows.

Fig. 5 is a detail view, in elevation, of the moisture controlling means.

The construction illustrated in the drawings as an embodiment of our invention, we believe to be the simplest and best form, but the invention may have expression in somewhat different mechanical form without departing from the spirit of the invention. 60 65

The machine as illustrated comprises a suitable supporting structure as shown at 10, preferably of angle members; with one end of the table or supporting structure provided with a bracket 11, on which a portion of an electric motor 12 is mounted. The motor-shaft is provided with a gear 13 which meshes with a large gear 14, rotatably mounted at the end of the table or supporting frame of the machine. The shaft on which gear 14 is secured is also provided with a small gear 15, which meshes with a gear 16 secured to the end of a shaft which is provided with a clutch 17. Clutch 17 is 70 75 adapted to be controlled from the discharging end of the machine by means of a foot lever 18 connected to a bell-crank lever 19, secured to the supporting frame of the machine; the clutch being normally out of 80 clutching position through the action of a spring 20 secured to the end of a lever 21, to which one end of link or rod 22 is also secured; the lever 21 being pivoted on the frame of the machine as shown in Fig. 1 90 95 and controls the sliding portion of the clutch which is feathered on a shaft to which a gear 23 is secured; the latter meshing with a similar gear 24. The gears 23 and 24 are operatively secured to the ends of worms 25 and 26, respectively, which are rotatably mounted in the receptacle portion of the machine. In order that the butter or butter substitute may not be discolored or affected, it has been found necessary to con-

struct the worms or screws 25 and 26, as well as the receptacle portion of the machine, of wood and for that reason the receptacle portion comprises a plurality of blocks 27 and 28 secured together in any suitable manner. These blocks are provided with a pair of substantially semi-cylindrical grooves; the grooves of one block registering with those of the other; the grooves forming channels of dimensions just sufficient to accommodate the worms or screws and permit free rotation thereof; while the grooves or channels, which are disposed parallel with each other and in the same horizontal plane, are arranged in communication with each other by means of a longitudinal groove disposed substantially in the same plane as the longitudinal axes of the worms, as shown at 29, in Fig. 4.

The worms 25 and 26 are alike in construction, being both formed with a special groove or spiral, namely, with what may be called the forward side of the spiral, made at a very acute angle to the vertical so as to provide an almost flat pressure applying side 30, thus providing the greatest amount of concavity adjacent the forward side 30, with the concavity becoming rapidly shallower as it approaches the rear side 31 of each spiral. The particular type of worm shown and described results in a more uniform and fast feed of the product introduced through the hopper 32. It has been found in practice, that uniformity and positiveness of feed in machines of the character to which our invention relates, depends to a considerable extent on the formation of the hopper end of the worm or screw channels and for that reason the upper member or block 27 adjacent the hopper 32 is cut away at an inclination so as to provide the considerably flared orifice as at 33 for the grooves. With this formation of the inlet or feeding end, pressure on the butter or butter substitute is retarded and the rolls or worms are enabled to rapidly take up the butter and cause it to be fed through the machine in a uniform manner, thereby insuring a consistency in the texture and weight of the prints of butter provided by the machine.

The worms 25, 26, terminate at the ends of the blocks or members 27 and 28, where the machine is provided with a moisture distributing element which also induces a proper blending of the product. The element is preferably in the nature of a metal plate 34, of predetermined thickness and provided with a plurality of similar perforations of predetermined diameter and equi-distances apart as shown at 35 in Fig. 5; the perforations being disposed throughout that portion of the plate which registers with the open ends of the grooves or

channels in which the worms 25 and 26 are located, see Fig. 3. The plate 34 is shown provided with bolt-holes at 36 in the marginal portion, which enable the plate to be securely bolted to members 27, 28 by bolts which also secure the molding head 37 to the delivery end of the members.

Our improved plate 34 causes the butter or butter substitute to be forced into the molding head 37 in vermicular form; the various particles being subsequently brought together into more or less compact form through the action of the regulable molding head 37.

By employing the foraminated plate or member 34, the desired amount of moisture can be provided in the finished product, as the moisture adhering to the pencil like portions and that passing through the plate, will be "pocketed" as it were between the numerous vermicular portions of butter which are brought together into a composite mass by the molding head 37. With our improved plate, a larger percentage of moisture is maintained within the product than would otherwise be the case; while at the same time, the plate, in conjunction with our improved rolls or worms and channel or groove construction, results in a better blending of the butter and provides a product of finer and smoother grain or texture possessing the desired amount of moisture content.

As a result of our improved machine, the use of a separate blending machine is obviated and the necessity of handling the butter or butter substitute for blending and printing is entirely eliminated. With our improved machine, the blending and printing of the butter is accomplished by a single machine and operation, thereby saving considerable time and expense and at the same time obviating the necessity of manual manipulation by operators having salt sores; the use of our improved machine therefore resulting in a more sanitary product than has heretofore been the case.

The size and width of the butter discharging from the molding head may be regulated by regulable throat-members which may be arranged and operable substantially similar to those shown and described in the pending application of one of the applicants and bearing Serial #293,712; the machine being capable of producing varying sized prints.

Our machine with its improved construction of feeding end and special construction of worms, produces a positive self-feeding machine which overcomes the difficulties heretofore encountered in obtaining uniformity of feed because of the resistance offered at the introducing or feeding end of machines as heretofore constructed; while at the same time both labor and expense are

saved and a more uniform product possessing the necessary amount of moisture and desired blend is produced in a less period of time.

- 5 The finished and formed butter or butter substitute is discharged from the throat of the molding head onto a series of freely rotating rollers shown at 38, mounted as shown in Fig. 1, at which point the butter is 10 cut into the desired prints and then discharged onto an endless belt 39; the endless belt being driven from a pulley 40 mounted on a trunnion to which bevel gear 41 is secured, which meshes with a bevel gear 42 15 secured to the end of a shaft 43 driven by means of a gear 44 which meshes with the gear 16; the construction causing a positive and proper driving of the endless element 39, commensurate with the speed of operation 20 of the remainder of the machine.

In addition to providing wooden worms or screws of the particular construction shown and described, the worms are not only arranged to operate in unison at the same 25 speed and in opposite directions, but the spirals of one worm are preferably arranged in staggered relation with the spirals of the other worm as shown in Fig. 2, thus greatly assisting in the proper operation 30 and positive feeding of the butter along the grooves of the main portion of the machine and thence through the foraminated member or plate 34. It will be understood 35 of course, that the plate 34 is preferably of substantial thickness to induce proper action in separating the butter into the vermicular portions described and also permit moisture to pass through to the molding head side of the plate, where it is entrained 40 with or caused to adhere to the various butter portions and thereby enveloped or incased when said portions are brought into compact form by the molding head.

What we claim and wish to secure by 45 Letters Patent is:

1. In a machine of the character described, a main body portion provided with a pair of cylindrical grooves arranged parallel and in communication with each other 50 at a point in line with the longitudinal axes of said grooves, and a wooden screw or worm disposed lengthwise of each groove, with the spirals of one worm arranged in staggered relation with those of the other, the grooves or spaces intermediate of the spirals of said worms being deeper adjacent the forward sides of the spirals than at the rear sides thereof.

2. A machine of the character described, 60 comprising a main body portion provided with a pair of cylindrical grooves disposed parallel and in communication with each other throughout the lengths thereof, a wooden worm or screw rotatably mounted

in each groove, with the spirals of one worm 65 arranged in staggered relation with those of the other, the worms being grooved intermediate of the spirals to a greater depth adjacent the forward sides of the spirals, a foraminated plate secured at the delivery 70 ends of said cylindrical grooves whereby the butter is separated into vermicular portions, and a molding head disposed beyond said plate whereby the vermicular portions are brought together with the adhering 75 moisture incased therebetween.

3. In a machine of the character described, a main body portion provided with a pair of cylindrical grooves disposed parallel with each other from end to end, the 80 top of said portion at one end being provided with a feed-opening having a gradually and forwardly slanting wall to provide a flared connection with the cylindrical grooves, a pair of screws or worms, composed of wood, disposed lengthwise of said grooves and provided with spirals approximating the perpendicular to the longitudinal axes of said worms, while the grooves intermediate of the spirals are deeper adjacent the forward sides of the spirals, and a molding head removably secured at the delivery ends of the grooves in the main body portion, communicating with both grooves and provided with an adjustable 90 delivery orifice.

4. In a machine of the character described, a main body portion provided with a pair of cylindrical grooves arranged parallel and in communication with each other, 10 a wooden screw or worm extending lengthwise throughout each groove, the spirals of one worm being arranged in staggered relation with those of the other worm, means whereby both worms are rotated in unison, 10 in opposite directions, a molding head removably secured to the delivery ends of said grooves, and moisture distributing means disposed intermediate of said head and the main body portion whereby the 11 butter is given vermicular form while being discharged into said head.

5. A machine of the character described, comprising a horizontally disposed main portion composed of wood and provided with a pair of cylindrical grooves arranged parallel and in communication with each other, said grooves being provided at one end with a feed opening flared forwardly at the bottom thereof, a wooden worm rotatably mounted in and extending lengthwise of each groove and provided with spaces or grooves intermediate of the spirals of greater depth adjacent the forward sides of the spirals, the spirals of one worm being arranged in staggered relation with those of the other worm, means whereby the worms are rotated in opposite directions, a

uniformly perforated plate of predetermined thickness disposed at the delivery end of the worm whereby the butter is separated into a plurality of vermicular portions, and a tapered molding head secured to the main portion in abutting relation with said plate, adapted to force the vermicular portions of butter into a compact mass so as to incase the moisture entrained with said vermicular portions.
